UNITED STATES PATENT OFFICE.

WILLIAM B. POWELL, OF CLEVELAND, OHIO, ASSIGNOR TO THE SHERWIN-WILLIAMS COMPANY, OF CLEVELAND, OHIO, A CORPORATION OF OHIO.

DESIGN FOR A CARD.

47,828.

Specification for Design.

Patented Sept. 14, 1915.

Application filed June 30, 1915. Serial No. 37,387. Term of patent 3½ years.

To all whom it may concern:

Be it known that I, WILLIAM B. POWELL, a citizen of the United States, and a resident of Cleveland, county of Cuyahoga, and State of Ohio, have invented a new, original, and ornamental Design for Cards, of which the following is a specification, reference being had to the accompanying drawing, forming part thereof.

In said annexed drawing the single figure there appearing, is a plan view of the card.

I claim:

The ornamental design for a card as shown.

Signed by me this 28 day of June, 1915.

WILLIAM B. POWELL.
